DISPLAY DEVICE

John Henry Wise, Joliet, Ill., assignor to American Can Company, New York, N. Y., a corporation of New Jersey

Application November 1, 1934, Serial No. 751,038

5 Claims. (Cl. 206—79)

This invention relates generally to an article of manufacture and more particularly to a device or assembly for holding, shipping and displaying a multiplicity of articles such as receptacles.

An object of the invention is the provision of a self-contained advertising display card, plate or board for removably holding articles such as containers upon it by interengagement of projecting parts or flanges on the articles to be held and on the card so that the articles held cannot be accidentally dislodged or shifted while on exhibition or during shipment and yet may be readily removed when desired.

Another object of the invention is the provision of a display card of simple construction which is particularly adapted for use with containers formed with projecting edges, joints or flanges such as end seams or the like, or counter sunk or recessed ends, the projecting edges of the container cooperating with projecting tongues or flanges formed in the card for holding and locking the containers within openings formed in the card.

Still another object of the invention is the provision of a display holder for containers, which may be formed from inexpensive material such as cardboard, which is formed with openings of a shape to conform to the shape of the container to be held and which has integral locking projections formed thereon which cooperate with standard parts of the container and with said openings to produce a firm locking engagement between holder and container without the employment of extra attachments.

Numerous other objects and advantages of the invention will be apparent as it is better understood from the following description, which, taken in connection with the accompanying drawing, discloses a preferred embodiment thereof.

Referring to the drawing:

Figure 1 is a front perspective view of a display card or article holding device embodying the instant invention;

Fig. 2 is a vertical sectional view taken substantially along the line 2—2 in Fig. 1; and

Fig. 3 is a horizontal sectional view taken substantially along the line 3—3 in Fig. 2.

The display device is closed in the drawing as a preferred embodiment of the invention, comprises a display card or plate 11 (Fig. 1) of substantially rectangular shape and dimensioned to hold a predetermined number of articles such as containers for shipment or display.

The card 11 is preferably formed in a single piece by a suitable stamping or cutting operation from suitable material such as stiff cardboard. By the same or an additional operation are formed a series of parallel rows of article or container receiving openings 13, three rows of four openings each being exemplified in Fig. 1. Each of these openings 13 is defined by opposed parallel vertical edges 14 which merge at their extremities into rounded corner edges 15.

Between the upper rounded edges 15 the material of the card is extended downwardly to form a relatively narrow container engaging flange or tongue 16, having a horizontal edge 17, which further defines the opening 13. Between the bottom rounded edges 15 the material of the card is projected upwardly to form a relatively wide container engaging flange or tongue 18, which is bent or creased along a horizontal line 19, parallel with the edge 17, so that the wider tongue 18 is divided into a vertical tongue portion 21 and a horizontal tongue portion which latter can be projected outwardly at a substantially right angle to the vertical tongue portion to form a container supporting shelf 22.

The card 11 is supported in desired display position by a triangular shaped bracket or brace 12 (Fig. 1) hingedly connected in any suitable manner to the vertical center of the rear side of the card 11 and may be folded flat against the rear side for packing or shipping.

A preferred form of container A to be held and displayed by the card 11, comprises an oblong body, having wide flat front and rear walls *a* and *b* joined by two rounded narrow sides *c* and also having countersunk or recessed end closures *d* secured to the open ends of the body A by crimping or seaming or in any suitable manner to provide with the body walls one form of projecting edges or joints *e* (Fig. 2). Other forms of projecting edges or joints may be provided readily by various and well known modes of forming end closures and joining them with the body walls. In the container illustrated one end closure is formed with a dispensing opening, closed by means of a friction plug C, which is one of many suitable closures which may be employed with containers having projecting edges or flanges.

To assemble the container A with the display card or holder 11, the projecting upper edge or flange *e*, formed by the rear wall *b* and the recessed top closure *d*, is slipped behind the depending tongue 16, the edge 17 of the latter preferably contacting with the horizontal panel of the

top closure *d*. The projecting lower edge or flange *e*, formed by the rear wall *b* and the recessed bottom closure *d*, is inserted behind the vertical part of the tongue *18*, so that the corner 5 in the tongue *18* formed by the parts *21* and *22* engages the corner formed by the recess of the bottom closure and the horizontal or shelf part *22* of the tongue *18* lies flat against the flat panel of the bottom closure and the free edge of the tongue 10 *18* contacts with the projecting lower edge or flange *e* formed by the front wall *a* and the recessed bottom closure. Thus positioned, the container body *A* extends partially through the opening *13*, opposed wall parts of the container body 15 contacting with the vertical edges *14* and being supported thereby.

It will thus be seen that cooperation exists between the upper and lower tongues *16* and *18* and the opening *13* and the side edges *14* to securely 20 clamp the container *A* in assembled or locked position. The tongue *16* resists upward and forward shifting, the tongue *18* through its vertical and horizontal parts resists downward, forward and rearward displacement and the edges *14* cooperate 25 in a niche-like manner to prevent displacement of the containers during shipment, handling, or while on display upon a sales counter.

When it is desired to remove a container from the holder or display board, the locking tongue *18* 30 is first pulled down out of engagement with the projecting front edge *e* and the flat panel of the bottom closure. This action also bends forward the short vertical part *21* of the tongue *18*, thus 35 freeing the lower part of the container. It is then only necessary to exert a slight forward and downward pull to free the upper end of the container from the tongue *16* and thus completely release the container from its clamped position in the opening *13*.

It will be understood that the dimensions of 40 the openings *13* and the locking tongues *16* and *18* may be changed to correspond to the dimensions of containers desired to be held or displayed.

It is thought that the invention and many of its 45 attendant advantages will be understood from the foregoing description, and it will be apparent that various changes may be made in the form, construction and arrangement of the parts without departing from the spirit and scope of the invention or sacrificing all of its material advantages, the form hereinbefore described being merely a 50 preferred embodiment thereof.

I claim:

1. A device for holding, displaying or shipping 55 containers having projecting edges, comprising a card having a series of openings into which containers may be inserted, and a pair of opposed tongues carried by said card adjacent each of said openings for engaging the projecting edges of a 60 said container to lock the container in position upon the card, one of said tongues having a por-

tion arranged in the plane of the card and having another portion extending at an angle to said first mentioned portion.

2. A device for holding, displaying or shipping 5 containers having projecting edges, comprising a card having an opening adapted to receive a container, said opening being defined by side edges and a pair of opposed tongues, said tongues being adapted to interlock with said projecting container edges, thereby clamping a side of said container against said side edges to hold the container in position upon the card, one of said tongues having a portion arranged in the plane of the card and also having a portion formed integrally with said first mentioned portion and extending at an angle thereto. 10 15

3. A device for holding, displaying or shipping 20 containers, comprising in combination, a card formed with an opening adapted to receive a container having opposed projecting edges, a pair of 25 opposed tongues carried by said card and extending into said opening for engaging said projecting container edges in the plane of said card and a locking flange formed integrally with one of said tongues and extending transversely therefrom and 30 from the plane of said card and engaging a projecting container edge outside of the plane of the card for locking said container against movement in said opening.

4. A container holding and display assembly 30 comprising in combination, a supporting plate having an opening substantially of the shape of the container to be held and adapted to surround said container in a frame like manner, said container having end closures with flat parts and 35 projecting edges, a plate extension adjacent one side of said opening to engage one end edge of the container, a plate extension adjacent an opposed side of said opening to engage the other end edge of the container and being further extended to 40 also engage a flat part of said other end, said opening and said plate extensions cooperating to removably lock said container in position upon said plate.

5. A container holding and display assembly, 45 comprising in combination, a supporting plate having an opening of a shape to receive and surround a container, said container having opposed ends provided with recesses, a tongue extending from said plate and engaging the recess of one of 50 said ends and an opposed tongue on said plate engaging the recess of the other of said ends, said opening and said tongues cooperating to removably hold said container in position upon said plate, one of said tongues having an integral portion disposed in the plane of the plate and another portion extending substantially at right angles to 55 said first mentioned portion and adapted to support said container at a locality spaced outwardly from said plate.

JOHN HENRY WISE.
